UNITED STATES PATENT OFFICE

119,054

DESIGN FOR AN EDIBLE FOOD SHELL

Benny B. Tolmack, San Francisco, Calif.

Application December 16, 1939, Serial No. 88,948

Term of patent 14 years

To all whom it may concern:

Be it known that I, Benny B. Tolmack, a citizen of the United States and a resident of the city and county of San Francisco, State of California, have invented a new, original, and ornamental Design for an Edible Food Shell, of which the following is a specification, reference being had to the accompanying drawing, forming part thereof.

Fig. 1 is a plan view of an edible food shell

showing my new design.

Fig. 2 is an end elevational view; and

Fig. 3 is a sectional view taken on line 3—3 of Fig. 1, the bottom half being shown in broken lines for convenience of illustration.

Both sides of the complete shell are alike.

I claim:

The ornamental design for an edible food shell, substantially as shown and described.

BENNY B. TOLMACK.
